WALL BRACKET FOR ARTICLE-SUPPORTING ARMS

Herbert C. Hogrebe, St. Louis, Mo., assignor to Dazor Manufacturing Corp., St. Louis, Mo., a corporation of Delaware

Filed Apr. 7, 1969, Ser. No. 16,591

Term of patent 14 years

Int. Cl. D8—03

U.S. Cl. D8—233

FIG. 1 is a perspective view of a wall bracket for article-supporting arms showing my new design;

FIG. 2 is side elevational view thereof, the article-supporting arms being shown partially, and in broken lines for illustrative purposes only, and the opposite side being the same;

FIG. 3 is a front elevational view thereof;

FIG. 4 is a top view thereof, and

FIG. 5 is a rear view thereof.

I claim:

The ornamental design for a wall bracket for article-
